COMBINED ENGINE CYLINDER VALVE AND FUEL INJECTOR

John Dickson, Ferndale, Mich., assignor to General Motors Corporation, Detroit, Mich., a corporation of Delaware

Application April 9, 1941, Serial No. 387,710

5 Claims. (Cl. 123—139)

This invention relates to internal combustion engines with injection of fuel into the engine cylinders, and particularly to a combined engine cylinder valve and fuel injector for such an engine.

In compression ignition engines especially, with combustion chambers of small volume, it is sometimes difficult to find space for the injector and the necessary engine cylinder valves communicating with the combustion chamber. When the injector is centrally disposed in the cylinder head, as it is desirable that it should be, there is frequently insufficient space left for valves of adequate area.

The object of the invention is an engine poppet valve combined with a fuel injector so that both the valve and the fuel injector may be arranged in the space taken up by the valve alone, in the wall of the combustion chamber, and both may be centrally disposed in a cylinder head.

Another object of the invention is a construction in which the plunger of the injection pump and the valve are actuated by means common to both of them.

Another object of the invention is a combined engine valve and fuel injector, containing a fuel reservoir for the injector, through which fuel is continuously circulated to cool the valve.

A further object of the invention is a construction in which the pump plunger and a spindle for the valve are both reciprocable in a stationary fuel pump cylinder.

A more specific object of the invention is a construction in which the pumping space is between the pump plunger and the valve spindle, and the valve is opened by direct thrust of the plunger on the spindle after delivery of fuel to an injection valve has been terminated by the opening of a port through the pump cylinder wall by the plunger.

The above and other objects of the invention will be apparent as the description proceeds.

According to the invention, the valve spindle extends into a stationary fuel pump cylinder, and there is a duct through the valve spindle from the pump pressure space to the injection valve embodied in the valve head and the injection nozzle which extends through the center thereof.

The valve is provided with a tubular stem enclosing the fuel pump cylinder barrel, and providing an annular space therearound which constitutes a fuel supply reservoir for the fuel pump and a cooling chamber for the exhaust valve.

A collar on the tubular valve stem forms a

seating for spring means normally holding the valve closed, while spring means between the tubular valve stem and the pump plunger normally hold the latter in a position spaced from the spindle to provide a pumping space therebetween. Means are provided to move the plunger towards the valve spindle to pump fuel from said space and then to open the valve by direct thrust of the plunger on the spindle.

10 The thrust of the pump plunger on the valve spindle is cushioned by displacement of the fuel remaining in the space between the pump plunger and the valve spindle, after the injection of fuel into the engine cylinder has been terminated.

15 The drawings show the application of the invention to a two-cycle Diesel engine having piston controlled inlet ports in the cylinder wall and a fuel injector which is generally of the kind shown in U. S. Patent No. 1,981,913, embodied in 20 the exhaust valve in the cylinder head.

In the drawings—
Figure 1 is a sectional elevational view showing the combined exhaust valve and injector mounted in the cylinder head of the engine, and 25 provided with suitable operating gear.

Figure 2 is an enlarged sectional view of the combined exhaust valve and injector showing the position of the parts with the pump plunger at the top of its stroke (i. e., the end of its suction stroke.)

30 Figure 3 is a view similar to Figure 2 but showing the position of the parts with the pump plunger at the bottom of its stroke (i. e. beyond the end of its delivery stroke), and the exhaust valve fully open.

35 The engine frame 1 includes a cylinder 2 within which is a piston 2'. Secured to the engine frame 1, by bolts such as 3, is the cylinder head 4.

40 Mounted in the cylinder head 4 is an exhaust valve 5 for a port 6 through which, when the valve is open, the exhaust gases pass from the engine cylinder 2 through the passage 7 to the exhaust manifold 8 and thence to the atmosphere. The cylinder head is provided with suitable water cooling passages such as 9.

45 The exhaust valve 5 has a tubular stem portion 10 of relatively large diameter, sliding in a tubular guide 11 having a flange portion 12 in a pocket 14 drained by a duct 15 in the cylinder head 4.

The valve 5 is normally held closed on its seating 16 by springs 17 and 18.

50 The springs 17 and 18 bear on the flange 12, with their opposite ends thrusting against a collar 19 which is held on the tubular stem portion

10 of the valve by the two halves of a split ring 20 which engage an annular groove in the exterior circumference of the tubular stem portion 10, and the shoulder of a counterbore in the collar 19.

The pocket 14 has a cover 25 having a boss portion 26 extending into the tubular stem 10 of the valve.

The boss portion 26 serves as an additional guide for the valve 5 on the inside of the tubular stem 10.

An extension 30 of the portion 26 is of reduced diameter and projects further into the tubular stem 10 of the valve, there being an annular space 31 between the extension 30 and the tubular stem. The extension 30 constitutes a fuel pump cylinder barrel for a plunger 35 which reciprocates in a cylinder bore 36 through the parts 25, 26 and 30.

The bore 36 in the cover 25 is counterbored to form a pocket 37 for a pinion 38. The plunger 35 is "splined" in the pinion 38 so that it may be turned thereby, but is capable of longitudinal reciprocation therethrough. The pinion 38 is retained in the pocket 37 by a plate 39, and may be angularly turned for adjustment of the beginning of injection in known manner by a rack 40 which can slide back and forth in a groove in the cover 25.

Secured to the head 45 of the plunger 35 by a spring ring 46 is a seating collar 47 for a spring 48. The seating collar 47 is guided in a tubular extension of the cover 25, and is retained therein by a spring ring 49.

The spring 48 does not react on the cover 25, but is seated, at its end opposite to the seating collar 47, on a seating 50 through which the plunger 35 slides. The seating 50 is subtended on three legs such as 53 at 120° to each other, which slide in holes through the cover 25 and, in effect, are an extension of the tubular stem 10 through the cover 25.

The head of the exhaust valve 5 is bored and counterbored for a nozzle piece 60, a valve seat piece 61, and a spindle 62 for the exhaust valve, all secured therein by a screwed sleeve 64. The exhaust valve spindle 62 reciprocates in the bore 36 for the end of which it is a movable closure.

Two spaced ports 70 and 71 connect the bore 36 of the cylinder barrel 30 with the annular space 31, the end of which is closed by the boss portion 26. The port 70 is provided with a readily renewable shroud or "spill deflector" 72, which shields the side of the tubular stem 10 from the high pressure discharge through this port when it is opened by a control edge on the plunger to relieve the pressure in the pumping space to terminate injection.

A duct, comprising drilled holes 74 and 75 in the cover 25 and the boss portion 26 respectively, serves for the supply of fuel to the annular chamber 31 from any suitable low pressure source of supply, and a similar duct comprising drilled holes 77 and 78 through these parts serves for the return of excess fuel to the source of supply. There is thus at all times a continuous flow of fuel through the annular chamber 31, so that the valve is effectively cooled while the fuel is heated, and there is no opportunity for the accumulation of any air or gas bubbles in this annular chamber which forms a reservoir for the fuel pump.

The pump plunger 35 has at its lower end an annular groove 80 dividing the circumferential surface of the plunger into two parts. The

lower surface is bounded by the bottom circumferential edge 81 and a circumferential edge 82, while the upper surface has a helical edge 83. A duct 85 in the plunger connects the annular space 80 between the edges 82 and 83 with the pumping space 86 between the plunger and the valve spindle.

A drilled hole or duct 87 in the valve spindle 62 connects the pumping space 86 with the injection nozzle 88 through a chamber 89 in the valve seat piece 61 and a chamber 90 in the nozzle piece 60.

There is a disc type check valve 91 in the chamber 89, and an injection valve 92 loaded by a spring 93 seated on a filling piece 94 in the chamber 90. The filling piece 94 is grooved for the flow of fuel therethrough to the nozzle 88, and reduces the volume of the chamber 90 to a desired minimum. The check valve 91 freely permits flow of fuel to the injection valve 92 while preventing back flow through the duct 81 which might occur if the injection valve failed to seat at such times as the pressure in the engine cylinder 2 exceeds the pressure in the fuel system.

The plunger 35 is actuated on its downward delivery stroke by any suitable driving means such as the cam 97 with push rod 98 and rocking lever 99 with roller 100. It will be noted that the cam is of the requisite form to give injection delivery stroke movement of the plunger 35, followed by further exhaust valve opening movement thereof, with suitable dwell periods between these movements.

In operation, fuel at a small head of pressure from any suitable source of supply (not shown) is supplied to the annular chamber 31 through the duct 74, 75. In the position shown in Figure 2, the plunger 35 is at the top of its stroke (i. e., the end of its suction stroke), and has uncovered the port 70 allowing fuel oil to flow into the pumping space 86 over and above the fuel always remaining in the duct 81, and the chamber 89, and to rise through the duct 85 and into the annular space 80 in the plunger. As the plunger descends, the edge 81 first covers the port 70, and then fuel oil and any air or gas bubbles mixed therewith is pumped from the space 86 up through the duct 85 and out through the port 71 back into the annular chamber 31 until the edge 83 covers the port 71. At this point, and there now being no other outlet from the pumping space, the pressure rises rapidly in the pumping space and its connection with the chamber 89 closed by the spring loaded injection valve 92, until the pressure thereon is sufficient to open the valve and the fuel is injected into the engine cylinder through the nozzle 88.

The injection continues under the influence of the downwardly moving plunger, until the edge 82 uncovers the port 70 which now functions as a pressure relief port terminating the injection and bypassing the remaining fuel oil delivered by the plunger from the pumping space, through the duct 85 into the annular space 80 and back into the annular chamber 31.

Upon further downward movement of the plunger, the fuel oil in the space between the plunger 35 and the valve spindle 62 is displaced out through the port 70 until there is no longer any such space and the plunger 35 is in contact with the valve spindle 62. Up to this point, movement of the pump plunger has been accompanied by compression of the spring 48, the

springs 17 and 18 of the exhaust valve and the cylinder compression pressure on the exhaust valve head being sufficient to hold the exhaust valve on its seat against the fluid injection pressure on the end of the exhaust valve spindle 62. From this point onwards however, the pump plunger thrusts directly on the exhaust valve spindle 62 and opens the exhaust valve 5 against the pressure of springs 17 and 18, to the position shown in Figure 3, without further compression of spring 48, because there is no longer any relative movement between the plunger 35 and the exhaust valve 5, and the spring 48 is mounted therebetween.

From the position shown in Figure 3, and as the highest part of the cam 91 moves away from the push rod 98, the springs 17, 18, and the spring 48, successively close the exhaust valve 5 and return the plunger 35 to the end of its suction stroke, ready for the next cycle of operation.

I claim:

1. In a combined engine cylinder valve and fuel injector, a stationary fuel pump cylinder, a pump plunger, a spindle for said valve, said plunger and spindle being reciprocable in said pump cylinder, means normally holding the valve closed, means normally holding the pump plunger in a position spaced from the spindle to provide a pumping space therebetween, and means to move the plunger towards the spindle to pump fuel from said space and then to open

said valve by direct thrust of the plunger on said spindle.

2. The combination according to claim 1 in which the valve has a tubular stem enclosing the stationary fuel pump cylinder and providing an annular space therearound, there being a fuel inlet and a fuel outlet to said space through which fuel is continuously circulated to cool said space, and at least one port through the wall of the pump cylinder, controlled by the pump plunger, for the flow of fuel between the said annular space and the pumping space within the pump cylinder.

3. The combination according to claim 1 including an injection valve to which fuel is pumped from the pumping space, and a port in the wall of the fuel pump cylinder controlled by the plunger; said plunger having an annular groove in communication with the pump pressure space, and said port being opened by an edge of the annular groove to terminate delivery of fuel to the injection valve before the plunger makes contact with the spindle.

4. The combination according to claim 1, in which there is an injection nozzle in the head of the valve and a duct through the valve spindle from the pumping space to said nozzle.

5. The combination according to claim 1, in which there is an injection nozzle in the head of the valve, a duct through the valve spindle from the pumping space to said nozzle, and a valve in said duct.

JOHN DICKSON.
